PENCIL BOX WITH BUILT-IN SHARPENER

Alex. A. Roger, Beverly Hills, Calif., assignor to
Spengler-Loomis Manufacturing Company,
Rockford, Ill., a corporation of Illinois

Application June 16, 1951, Serial No. 231,974

7 Claims. (Cl. 120--1)

1

This invention relates to a new and improved pencil box with built-in sharpener.

The principal object of my invention is to incorporate the pencil sharpener in one end portion of the pencil box without adding too much to the overall size and weight and also without involving too much added expense, and at the same time provide the sharpening facility as well as the facility for dumping of chips in the handiest form, so that a child will have no difficulty whatsoever in operating the sharpener and emptying the accumulated chips from time to time.

The sharpener compartment built in one end of the main body portion of the box, in accordance with my invention, has the sharpener assembly rotatably mounted therein and arranged to be turned by means of a specially designed crank having a foldable handle adapted to lie close to the side of the box in its out-of-the-way position, and the compartment is normally closed by the cover-slide, which works in grooves provided therefor in the top of the box on the main body portion and also in registering grooves provided in the laterally swingable top section that is pivoted on the main body portion of the box near one end remote from the sharpener compartment, the cover-slide being provided with stop projections on opposite ends, which permit a very short travel of the slide in one direction in opening the sharpener compartment for the dumping of chips while keeping the pencil box otherwise securely locked closed, but allows longer travel in the other direction as required in opening the box properly for removal of pencils from the top or bottom pencil compartments while keeping the sharpener compartment securely locked closed. By locating the pivot for the swingable top section far enough inwardly from the outer ends of this section and providing a partition in the bottom section below this pivot, I have arranged to provide in the two sections three different length compartments, for long, short, and intermediate length pencils and other articles.

The invention is illustrated in the accompanying drawings, in which—

Figs. 1 and 2 are a top and side view, respectively, of a pencil box with built-in sharpener made in accordance with my invention;

Fig. 3 is a top view of the box, showing the cover-slide in one extreme position and the top section of the box swung to an open position affording access to either of the three storage compartments in the two sections of the box;

2

reserved for pencils and other articles, while the cover keeps the sharpener compartment securely locked closed against dumping of chips, and

Fig. 4 is a top view of the box showing the cover-slide in the other extreme position for dumping of chips from the sharpener compartment, while keeping the rest of the box securely locked closed.

The same reference numerals are applied to corresponding parts throughout the views.

Referring to the drawings, the reference numeral 5 designates the main body portion of the pencil box, which provides the lower section 6 for storage of pencils, erasers, and other articles, and 7 designates the pivoted top section intended for storage of longer pencils, rulers, and other articles, the compartment 8 in section 7 being longer than either of the compartments 9 and 10 in section 6. The partition 11 in section 6 provides a support for the pivot screw 12 relative to which the section 7 swings, and this partition is so arranged that a medium length compartment is provided at 9 and a short length compartment at 10, thus giving the child an opportunity to sort out his belongings according to length. A sharpener compartment 13 is provided in a housing 14 formed on one end of the main body portion 5, this housing being equivalent in depth to the combined depth of sections 6 and 7 of the pencil box, as clearly appears in Fig. 2, so that the open top thereof is in coplanar relationship to the open top of the pivoted top section 7, as required for the sliding back and forth of the cover-slide 15 in registering grooves 16 and 17 provided in the opposite sides of the open tops of the housing 14 and box section 7, respectively, the cover having tongues 18 on the longitudinal edges thereof slidably received in these grooves. Finger recesses 19 and 20 are provided in the top of the cover-slide 15 near the opposite ends thereof, to facilitate sliding the cover back and forth. The inner side 21 of the housing 14 is cut on an acute angle, and the inner end of the pivoted box section 7 is cut off on a matching angle, as indicated at 22, to permit swinging section 7 in only one direction when opening the pencil box, as appears in Fig. 3, and limit the return movement, as indicated in Figs. 1 and 4. Downwardly projecting stops 23 and 24 are provided on opposite ends of the cover-slide 15 to limit endwise movement of the slide in opposite directions by engagement with opposite sides of a transverse wall 25 on the inner side of the sharpener compartment 13. Thus, when the cover 15 is slid a short distance to the one limit

position, indicated in Fig. 4, where the stop projection 23 engages the wall 25, the sharpener compartment 13 is opened for dumping of chips but the pencil box is locked securely closed. On the other hand, when the cover 15 is slid a longer distance in the other direction to the limit position shown in Fig. 3, where the stop projection 24 engages the other side of the wall 25, the pencil box is unlocked for access to either of the three compartments 8, 9 and 10, but the sharpener compartment 13 is closed securely. Grooves 26 and 27 are provided in the end walls 28 and 29 of the pivoted top section 7 to allow passage of the stop projection 24 in sliding the cover 15 to the limit position, shown in Fig. 3, there being a depression 31 provided behind the wall 25, deep enough to accommodate the stop projection 24 in the said limit position and permit the cover 15 to be pulled back far enough to leave working clearance for the end of the pivoted box section 7. A similar groove 31 is provided in the end wall 32 of the sharpener compartment 13 to accommodate the stop projection 23 and allow the cover 15 to slide to the limit position shown in Fig. 4.

Any suitable or preferred design of crank-operated rotary pencil sharpener mechanism may be employed in the sharpener compartment 13. Thus, while I have shown a sharpener mechanism having a single cutter 33 designed to be driven by meshing engagement of a pinion meshing with an internal gear inside the stationary ring 34, relative to which the frame 35 carrying the cutter 33 is adapted to be rotated by means of a crank 36, to sharpen a pencil 37 entered in a guide opening in a face plate 38 secured to the box on the opposite side from the crank 36, the conventional two-cutter type sharpener having the two cutters thereof in converging relationship and disposed to cut on diametrically opposite sides of the pencil may be provided in lieu of the one shown. A face plate 39 suitably secured to the side of the box provides a bearing for the frame 35 to run in and also a mounting for the ring 34. The other face plate 38 need only provide a guide opening in coaxial relationship to the conical-shaped pencil receiving portion in the frame 35. The crank 36 is purposely designed to lie as close as possible to the side of the face plate 39, and the handle 40, which is in the form of a split ring, the opposite end portions of which are received in a transverse hole 41 provided in a pin 42 suitably swiveled in the outer end of the crank 36, is arranged to be folded into parallelism with the crank when not in use, as shown in full lines in Fig. 1, to take up less room and reduce the likelihood of the crank or handle getting caught on anything when the pencil box is being carried around or is being put away in a desk. This also facilitates packing of the pencil box in a shipping container.

From the foregoing description, it is apparent that the invention comprises two separate but pivotally interconnected unitary box structures. The first unitary box structure 5 has a first portion open at the top providing the two compartments 9 and 10 and a second open top portion providing the pencil sharpener compartment 13, the top of said first portion being at a level spaced substantially below the level of the top of the pencil-sharpener portion. The second unitary box structure which is pivotally mounted on the first box structure, provides the upper open top compartment 8. The top of this pivoted second box structure is at substantially the same level as the top of the pencil-sharpener com-

partment 13 so that the single lid 15 may cover both compartments 8 and 13 simultaneously. The grooves 17 on the second pivoted box structure constitutes a first track means to engage the lid 15 with freedom for the lid to slide longitudinally and the grooves 16 on the pencil-sharpener portion of the first box structure constitutes a second similar track means, these two track means being in alignment at the position of the second pivoted box structure that closes the first portion of the first box structure.

It is further apparent that the lid 15 is movable longitudinally to four different positions in the various uses of the pencil box and that the lid serves multiple functions at each of these four positions. The four positions of the lid and the functions of the lid at the four positions are as follows.

A first position of the lid 15, which may be termed a limit position, is illustrated in Fig. 4 where it can be seen that the lid 15 is retracted in one direction to uncover the pencil-sharpener compartment 13, the lid being retracted to the limit position at which the stop 23 on the lid abuts the transverse wall 25. It is to be noted that in the movement of the lid to this limit position, the stop 24 on the other end of the lid moves outward through the groove or recess 27 in the opposite end wall 29. At this first limit position, the cover slide 15 accomplishes the following purposes:

- (a) Uncovers the pencil-sharpener compartment 13 to permit dumping of pencil shavings therefrom;
- (b) Covers upper compartment 8 to prevent dumping of its content when the pencil shavings are dumped;
- (c) Locks the pivoted box structure in position closing the lower compartments 9 and 10 to prevent the dumping of the contents of these lower compartments when the pencil shavings are dumped.

At the second longitudinal position of the lid 15 shown in Fig. 1, the lid is in a central position relative to the pencil box with both of the stops 23 and 24 on the lid spaced away from the transverse stop wall 25 of the box structure. At this second or closed position of the lid 15, the lid serves the following purposes:

- (a) The lid closes the upper compartment 8 in the pivoted box section 7;
- (b) The lid closes the pencil-sharpener compartment 13;
- (c) The lid locks the second pivoted box structure against rotation relative to the first unitary box structure to keep the lower compartments 9 and 10 closed.

At a third position of the lid 15 that is not shown in the drawings, the lid 15 as viewed in Fig. 1 is retracted downward from its central closed position until only a minor portion of the lid remains in an engagement with the first track means or grooves 17 on the pivoted box structure. At this position, the lid serves the following purposes:

- (a) The lid closes the pencil-sharpener compartment 13 to confine the pencil shavings therein;
- (b) The lid being in engagement with both the first track means or grooves 17 and the second track means or grooves 16, locks the second pivoted box structure against rotation relative to the first box structure and thus keeps

the two compartments 9 and 10 closed to confine their contents;

(c) The lid exposes the upper compartment 8 to make its interior accessible.

The fourth position of the lid 15 in this progressive series of positions is shown in Fig. 3 where the lid is at a limit position determined by abutment of the stop 24 on the under side of the lid against the transverse wall 25. In this position the lid serves the following purposes:

- (a) The lid covers the pencil-sharpener compartment 13 to retain the pencil shavings therein;
- (b) The lid wholly exposes compartment 8 in the second unitary box structure;
- (c) The lid permits the second unitary box structure to pivot for the purpose of exposing the lower compartments 9 and 10 for access thereto.

My description and specific detail of a preferred practice of the invention will suggest to those skilled in the art, various changes, substitutions and other departures from the disclosure that properly lie within the spirit and scope of the appendent claims.

I claim:

1. In a pencil box of the character described, the combination of: a first unitary box structure having a first open top storage portion extending longitudinally from one end of the structure and a second open top pencil-sharpener portion extending longitudinally from the other end of the structure, the level of the top of said second portion being spaced above the level of the top of the first portion; a second unitary top box structure over said first portion of the first box structure with the top of the second box structure at substantially the same level as the top of said second portion of the first box structure, said second box structure being pivotally mounted on the first box portion to rotate laterally between a position closing said first storage portion and a position exposing the interior of said first storage portion; a lid dimensioned in length to cover both said second box structure and said second pencil-sharpener portion of the first box structure; a first track means on the top of said second box structure to retain said lid with freedom for the lid to slide longitudinally of the second box structure; and a second track means on the top of said second portion of the first box structure to retain said lid with freedom for the lid to slide longitudinally of the first box structure, said two track means being positioned for alignment when said second pivoted box structure is in position closing said first portion of the first box structure, whereby said lid is longitudinally movable to four positions, namely, a first position sufficiently retracted from said pencil-sharpener portion of the first box structure to permit dumping of pencil shavings therefrom, but covering said second box structure to confine the contents thereof, the lid at said first position being in engagement with both said track means to prevent rotation of said second box structure out of its position closing said first storage portion of the first box structure, a second position centrally of the two box structures closing both said second box structure

and said pencil sharpener portion of the first box section, the lid at said second position being in engagement with both said track means to hold said second pivoted box structure in position closing said first portion of the first box structure, a third intermediate position partially retracted with respect to said second pivoted box structure for access thereto but in engagement with both said two track means to hold said second pivoted box structure in position closing said first box portion of the first box structure, and a fourth position completely retracted from said first track means on said second track means to cover said pencil sharpener portion and to free said second pivoted box structure for rotation relative to the first box structure to expose said first portion of the first box structure for access thereto.

2. A device as set forth in claim 1 which includes stop means to limit the movement of said lid at said first and fourth positions, respectively.

3. A device set forth in claim 1 which includes two stop means on said lid and stop means on said first box structure cooperating with said two stop means to limit movement of said lid at said first and fourth positions, respectively.

4. A device as set forth in claim 1 which includes stop means on said first box structure below the path of movement of said lid, a first inward projection on one end of said lid to abut one side of said stop means at said first position of the lid, and a second inward projection on the other end of the lid to abut the other side of said stop means at the fourth position of the lid.

5. A device as set forth in claim 4 in which the outer end of said first box structure is recessed to clear one of said lid projections and the other end of said second box structure is recessed to clear the other of said lid projections.

6. A device as set forth in claim 1 in which said first portion of said first unitary box structure is divided into at least two compartments by a transverse wall and in which said second box structure is pivotally mounted on said transverse wall.

7. A device as set forth in claim 1 in which at said second or closed position of the lid the vertical longitudinal cross-sectional configuration of the combined unitary box structures is rectangular, each of the two box structures being complementary parts of the rectangular configuration.

ALEX. A. ROGER.
